UNITED STATES PATENT OFFICE.

CHARLES W. STIMSON, OF NEW YORK, N. Y.

DESIGN FOR A JUNCTION-PLATE.

SPECIFICATION forming part of Design No. 23,799, dated November 13, 1894.

Application filed September 20, 1894. Serial No. 523,647. Term of patent 14 years.

To all whom it may concern:

Be it known that I, CHARLES W. STIMSON, a citizen of the United States, residing at New York, in the county of New York and State of New York, have invented and produced a new and original Design for Junction-Plates of Garment Attachments, of which the following is a specification, reference being had to the accompanying drawing, illustrating the same.

In the drawing there is illustrated a plan view of a junction plate constructed in accordance with my design. The junction plate consists of a thin plate, preferably of metal, and having a contour which is nearly or exactly circular, the edges being composed of arcs of one or more circles. Near the edges of the plate are three openings, two of which are slots, placed at an acute angle to one another, while the third opening is nearly or ex-

actly elliptical, and is situated adjacent to the more widely separated ends of the slots, the three openings forming, substantially, the outlines of a triangular figure. Within this triangular figure is a triangular opening.

The leading feature of my design consists in the circular or approximately circular contour of the plate, together with the openings in said plate arranged so as to form, substantially, a geometrical figure.

What I claim is—

The design for a junction plate herein shown and described.

In testimony whereof I hereunto set my hand in the presence of two witnesses.

CHARLES W. STIMSON.
